UNITED STATES PATENT OFFICE.

JULIUS H. BACH, OF CHICAGO, ILLINOIS.

APPARATUS FOR FACILITATING THE BURNING OF BRICK.

1,071,014.

Specification of Letters Patent. Patented Aug. 26, 1913.

Application filed October 11, 1912. Serial No. 725,272.

To all whom it may concern:

Be it known that I, JULIUS H. BACH, a citizen of the United States, residing at Chicago, in the county of Cook and State of Illinois, have invented certain new and useful Improvements in Apparatus for Facilitating the Burning of Brick, of which the following is a description, reference being had to the accompanying drawings, forming 10 a part of this specification, in which corresponding numerals of reference in the different figures indicate like parts.

The object of my invention is to provide an apparatus to facilitate the burning of 15 bricks in kilns whereby the operation may be rendered continuous and the heat and products of combustion from the burning kiln may, after being utilized for drying the green brick preparatory to burning, be carried off to a stack so as to fully conserve the 20 heat generated while preventing the dissemination of smoke and obnoxious gases which have heretofore attended the burning of brick in the open air. To these ends my 25 invention consists in the combination of elements hereinafter more particularly described and definitely pointed out in the claims.

In the drawings Figure 1 is an end view 30 of a shed and kiln showing the improved apparatus in connection therewith. Fig. 2 is a plan view of a kiln, drying room and stack, together with said improved apparatus, diagrammatically shown. Fig. 3 is a 35 side elevation of a portion of a kiln showing the movable hood and heat conduit. Fig. 4 is an end view in detail of a portion of that end of the hood which is adjacent to the conduit, the relative position of the latter being indicated in dotted lines, and Fig. 5 40 is a vertical section, taken upon the line 5 Fig. 4, viewed in the direction of the arrow there shown.

Referring to the drawings, 1, Fig. 1, represents an ordinary kiln shed having the 45 usual parallel rows of posts 2, which are extended lengthwise thereof and between which the kiln 3, of indefinite length is placed. Within and adjacent to the posts 50 2, and rigidly connected therewith by means of ties 4, are supplemental posts 5, the upper ends of which are considerably above the level of the top of the kiln and serve, among

other things, as supports for track beams, 6, 6, which are laid horizontally thereon for 55 the reception of the usual traveling crane, not shown, which is used for placing the dried brick in position in the kiln. Ties or plates 7, similar to ties 4, are attached in like manner to the posts 2 and 5, near the 60 level of the top of the kiln, but are extended inwardly beyond the posts 5, to form brackets for the support of the horizontal track beams 8, 8. A sheet metal hood, generally designated in the several figures by 65 9, is mounted at opposite ends on wheels 10, which are adapted to travel upon the tracks 8. The width of the hood is somewhat greater than that of the kiln, at the top, but its length may be indefinite. I prefer, 70 however, that it should be made to extend over about five or six of the ordinary arches 11, Fig. 3, of the kiln. Said hood is preferably composed of a plurality of arched portions 12, extending transversely of the kiln, 75 said arched portions being formed considerably higher at one end than at the other, as shown in Figs. 1 and 3. The left hand end of the hood is closed by means of an end plate 13, Fig. 3, the lower edge of which 80 is straight, while bottom plates 14 and 15, the latter of which is also shown in Fig. 5, are attached thereto and extended lengthwise of the kiln so as to project laterally over the edges thereof. Inasmuch as the 85 hood is adapted to travel upon a horizontal track lengthwise of the kiln, the height of the latter when built, should be adapted to that of the hood and its upper surface should be such as to barely allow for clearance to permit the hood to be moved over it. In Fig. 1, in order to avoid possible confusion, I have shown the space between the top of the kiln and the bottom of the hood 90 to be somewhat exaggerated in appearance. 95

Supported on beams 16, or in any approved way, is a horizontal conduit 17, Figs. 1, 2 and 3, preferably formed from sheet metal or other non-inflammable material, which is arranged to extend parallel to and 100 throughout the length of the kiln. Connected with said conduit and extending laterally therefrom upon the side next to the kiln, are a series of intake pipes 18, the distance between which corresponds to that 105 between the arches 11, so that the arches

and pipes will be in common vertical planes, as shown in Fig. 3. The outer ends of the pipes 18 throughout the length of the conduit, are connected to a common vertical plate 19, which is arranged parallel to the path of movement of the hood, 9 and in close proximity to its end, so that the space between the two may be as little as possible consistent with the movement of the hood. Circular openings are formed in the plate 19, for the reception of the ends of the pipe 18. Each of said intake pipes is provided with a damper 20, Fig. 5, pivoted in a well-known way in bearings therein, the stem of which is provided with a cross-bar 21, to the ends of which cords or chains 22, may be attached for the purpose of opening or closing it. The end of the hood next to the plate 19, is provided with an end plate 22, Figs. 4 and 5, having an opening 23, therein the height of which is preferably somewhat greater than the diameter of the pipes 18, while its length is considerably greater than said diameter as shown in Fig. 4. The purpose of the construction will be explained later.

An operating shaft 24, is journaled in bearings formed in brackets 25, 25, which are rigidly attached to the hood. Upon the opposite ends of said shaft are sprocket-wheels 26, 26, which are connected by means of sprocket-chains 27, 27, to sprocket-wheels 28, 28, upon the hubs of two of the wheels 10. A driving-wheel 29, is rigidly mounted upon one end of the shaft 24, and is provided with an endless chain 30, Figs. 1 and 4, which is adapted to be actuated by an attendant upon the ground.

At some arbitrary point, preferably midway between the ends of the conduit 17, is located a drying-chamber or kiln 31, Fig. 2, for drying the brick preparatory to burning it. Said chamber is connected with the conduit by means of an intake pipe 32. An outlet-pipe 33, serves to connect said drying chamber with a fan 34, adapted to be driven from any suitable source of power, which fan is in turn connected preferably by means of an underground conduit indicated by dotted lines 35, with a chimney-stack 36, of the usual construction.

The operation of said device is as follows: The kiln 3 is built in the usual way with dried brick laid in open or checker work to permit the passage of heat between them, some of the upper courses thereof being laid flatwise and closer together in a well-known manner, to partially restrain the draft at the top. The sides and ends of the kiln are protected by scoving as usual. When thus prepared the hood 9 is moved into position above the portion at the end where the fire is to be started. A predetermined number of arches beneath the hood are fired, when all of the dampers 20, in the pipes 17, except

those communicating with the hood, are closed. When this is done the fan 34, is started, thereby producing a suction upwardly from the arches through the kiln to the hood 9, and conduit 17 and thence through the drier to the stack. The heat and products of combustion being thereby carried through the course described. Upon burning a given section, the hood is moved on and additional arches are fired until the entire kiln is burned. By making the kiln of sufficient length the burned portion at one end may be cooled and removed and dried brick from the drying-kiln substituted therefor by the time the last arches are fired at the opposite end; thereby enabling the operation to be continuous. As fast as the brick is dried, it may be placed in the kiln for burning. The speed of the operation may be varied by increasing or decreasing the number of arches which are being fired at a given time, it being understood that the size of the hood may be varied and that no greater number of arches should be burned than can be covered by the area of the hood.

The reason for elongating the openings 23 in the plate 22 is to insure registration between the hood and the pipes 18, while the plate 19 is to prevent cold air from being sucked into the conduit at the end of the hood. It is obvious that the hood may be moved in either direction according to the end of the kiln at which the burning is commenced.

My improved apparatus not only enables the waste heat of the kiln to be utilized for drying the green brick but enables the burning to be continuous, insures a more uniform product instead of a dense volume of escaping smoke and vapor throughout the length of the kiln; I have found in practice that only a light and oftentimes scarcely perceptible vapor escaped from the top of the stack, which is carried off without injury to the atmosphere of the neighborhood.

I do not wish to be limited to the construction shown nor to the relative position of the conduit 17, inasmuch as either may be greatly varied without departing from the spirit of the invention.

Having thus described my invention, what I claim and desire to secure by Letters-Patent is:

1. In an apparatus of the class described, the combination with a kiln adapted to be progressively fired from end to end, of a traveling hood above said kiln, means for moving said hood in a horizontal plane lengthwise of said kiln, a conduit arranged parallel to the path of movement of said hood, said conduit having openings therein and in position respectively to communicate with the interior of said hood as the latter is moved, means for closing each of said openings independently

of the others, and means for causing a suction in said conduit, whereby the heat and products of combustion from the burning kiln may be drawn into the hood and carried away through said conduit.

2. An apparatus for facilitating the burning of brick in kilns, comprising a kiln adapted to be progressively fired from end to end, a hood arranged to be moved above the kiln as the fire is advanced in the arches, a conduit arranged parallel to the path of movement of said hood, means for operatively connecting said conduit with said hood as the latter is advanced, a chimney-stack and means for producing a suction in said conduit toward said chimney-stack.

3. An apparatus for facilitating the burning of brick in kilns, comprising in combination, a kiln in which the firing is advanced from arch to arch progressively in one direction, a hood arranged to be moved over the kiln as the fire is advanced in the arches, a conduit located parallel to the path of movement of said hood, said conduit having normally closed openings therein for communication with said hood, means for bringing said hood and conduit into communication with each other as the hood is advanced above the kiln, and means for producing a suction from said kiln into said hood and thence through said conduit to the atmosphere.

4. An apparatus for facilitating the burning of brick in kilns comprising in combination a kiln in which the firing is advanced progressively in one direction, a hood arranged to be moved over the kiln in conformity to the advance of the firing, a conduit located parallel to the path of movement of said hood, said conduit having normally closed openings therein for establishing communication between it and said hood, means for bringing said hood and conduit into communication with each other as the former is advanced above the kiln, a drying-chamber in communication with said conduit and means for causing a suction to produce a draft through said hood, conduit and drying-chamber to the open air.

5. An apparatus for facilitating the burning of brick in kilns comprising in combination a kiln in which the fire is advanced progressively from end to end, a hood arranged to be moved over the kiln as the firing in the latter is advanced, a conduit located parallel to the path of movement of said hood, means for bringing said conduit and hood into operative communication with each other as the hood is advanced above the kiln, a drying-chamber in communication with said conduit, a chimney-stack in communication with said drying chamber and means for causing a suction from said drying-chamber into said stack.

6. An apparatus of the character speci-

fied, comprising in combination a kiln in which the firing is advanced progressively from end to end, a hood, a horizontal way for supporting said hood above a kiln, means for causing the advancement of said hood upon said way, a conduit arranged parallel to the path of said hood, means for bringing said hood and said conduit into operative communication with each other as the hood is advanced upon the way, a drying-chamber in communication with said conduit, a chimney-stack in communication with said drying-chamber and a fan interposed between said drying-chamber and chimney-stack.

7. An apparatus of the character described, in which is combined a kiln in which the firing is advanced progressively from end to end, a hood, a substantially horizontal way for supporting said hood above a kiln, means for causing the advancement of said hood, normally closed branch pipes communicating with said hood as the latter is advanced opposite thereto, means for opening said pipes to form such communication between them and said hood, a drying-chamber in communication with said conduit, a chimney-stack and a fan for producing a suction from said drying-chamber to said chimney-stack.

8. An apparatus of the character described, in which is combined a kiln in which the firing is advanced progressively from end to end, a traveling hood mounted upon a way for supporting the same above a kiln, means of causing the advancement of said hood upon said way, a conduit extending throughout the length of said way, pipes communicating with said conduit, the open ends of which are in position to communicate with said hood as the latter is advanced, the number and respective positions of said pipes corresponding substantially to those of the arches in the kilns to be burned, means for opening and closing said pipes independently of each other, a drying-chamber, a chimney-stack and means for causing a suction from said drying-chamber into said chimney-stack.

9. In a device of the class described, the combination of an elevated way, arranged to permit a kiln to be built beneath the same in the direction of its length, a kiln in which the firing is advanced progressively from end to end, a hood mounted to travel in either direction upon said way, said hood having an opening in one side, means for actuating said hood, a conduit extending throughout the length of said way in operative proximity thereto, open-ended pipes communicating with said conduit, the open ends of which are adjacent to the pathway of said hood, to communicate with the openings in the side of the latter, means for preventing the admission of atmospheric air to

said hood, separate dampers in said open-ended pipes, a drying-chamber in communication with said conduit, a chimney-stack in communication with said drying-chamber and a fan for producing a suction from said drying-chamber to said chimney-stack.

In testimony whereof, I have signed this

specification in the presence of two subscribing witnesses, this 17th day of September, 1912.

JULIUS H. BACH.
